REFRIGERATOR

George J. Hopkins, Kendallville, Ind., assignor to
McCray Refrigerator Company, Kendallville,
Ind., a corporation of Indiana

Application October 19, 1938, Serial No. 235,711

2 Claims. (CL 240—6)

The present invention relates to refrigerators and more particularly to illuminated display refrigerator cases.

The primary objects of the invention are to provide a maximum of illumination within the case from a minimum of electrical energy expended; to provide novel and effective means for utilizing the light from a horizontal row of incandescent bulbs to illuminate upper and lower shelves within a refrigerated display case; to provide a means of illuminating the interior of the case without passing the light rays through a pane or panes of glass which would thus detract from the quantity or the quality of the illumination; to provide illuminating means for a display case which eliminates the possibility of glare in the eyes of an observer; to provide the novel combination of fluorescent light bulbs within refrigerated spaces; and, to provide an illuminated display refrigerator case improved in certain other respects hereinafter appearing.

An illustrative embodiment of the invention is shown in the accompanying drawings, wherein:

25 Figure 1 is a perspective view of a display refrigerator case embodying the invention;

Figure 2 is a sectional view thereof on line 2—2 of Figure 3, on a scale reduced from that of Figure 3 but enlarged over that of Figure 1;

30 Figure 3 is an enlarged fragmentary sectional view on lines 3—3 of Figures 1 and 2; and

Figure 4 is an enlarged fragmentary sectional view on line 4—4 of Figure 3.

Referring then to these drawings wherein like parts of the structure shown are designated by the same numerals in the several views, the display refrigerator case there shown is provided with a glazed front wall 10 whose triple spaced panes of glass 11 provide "dead air" insulation 12 between the interior and exterior of the case and afford customers visibility of merchandise displayed therein. These panes of glass 11 are secured in the window frame 13 of the case in spaced relation to each other as by U-shaped spacers 14 disposed between adjacent panes, all as best seen in Figure 3.

The rear wall of the case is provided with conventional sliding doors 15 disposed on tracks 16 in the rear wall of the case and having similar triple spaced panes of glass 17 therein. These doors 15 when in their closed positions, seal the opening in the rear wall of the case to thus complete the insulation of the region within the case.

55 This region within the case is refrigerated by

conventional coils 18 suspended from the inside top of the case and a drip pan 19 secured to the inside front and rear walls of the case is suspended below the cooling coils 18 to carry off water of condensation.

5 Supporting bars 20 secured to the inside front and rear walls of the case support a lower shelf 21 which slopes forwardly-downwardly and extends the length of the case. A second or upper shelf 22 may if desired and as shown be made in two sections 22a and 22b, the sections being supported at their inner ends by a supporting arm 23 secured to the inside rear wall of the case and supported at their outer ends by brackets 24 secured to the inside end walls of the case. 15 The upper shelf 22 likewise slopes forwardly-downwardly.

A dual-walled deflector 25 disposed in parallelism with and at approximately the same level as the upper shelf 22, extends the length of the 20 case and is supported at its center by an L-shaped bracket 26 secured to the supporting arm 23, the ends thereof being supported by screws 27 passing through flanges 28 on the deflector and threaded in the end walls of the case.

25 Light bulbs 29 mounted in sockets 30 are secured by brackets 31 and screws 32 passing therethrough to the inside wall 33 of the deflector 25. Wiring connections 34 supply electrical energy to the light bulbs 29 from a suitable source (not shown). The outer wall 44 of the dual walled deflector 25 conceals the means of attaching the deflector to the L-shaped bracket 26 and the brackets 31 to the deflector.

A plate 37 having flanges 38 secured to the 35 under side of the drip pan 19 extends the length of the case and is provided on its under side with a light reflecting surface such as a coating of white porcelain.

It will be seen that the lower shelf 21 and 40 merchandise supported thereby are directly illuminated by light rays from the bulbs 29 as indicated by broken arrows 39. The upper shelf 22 and merchandise thereon is illuminated by light rays from the bulbs 29 reflected from the 45 porcelain coated under side of the plate 37 as indicated by broken arrows 40.

The deflector 25 deflects light rays from the direction of the glazed front wall 10 of the case and these deflected rays likewise fall upon the 50 lower shelf 21 as indicated by a broken arrow 41. Thus the interior of the case and the merchandise on display therein are illuminated by light rays from a source in proximity thereto, and inasmuch as the intensity of light on the illumi- 55

nated surface varies inversely as the square of the distance from the source, a relatively small amount of light at the source suffices to brightly illuminate the case.

5. The light rays furthermore are not impeded nor reflected by intervening panes of glass as in earlier constructions, and the source of illumination is concealed from the eyes of observers so that glare is entirely eliminated.

10. Although the present construction may satisfactorily be used with ordinary filament light bulbs, the invention contemplates the use of fluorescent light bulbs whose heat emanation is relatively low and whose light emanation is relatively high as contrasted to the ordinary filament bulb, and which fluorescent bulbs may therefore be utilized within the refrigerated region without materially interfering with the refrigeration thereof.

15. It will thus be seen that effective and efficient means are provided for illuminating the interior of a display refrigerator case, that novel means are provided for illuminating vertically spaced shelves from a light source in proximity to said shelves and that the possibility of glare in the eyes of prospective customers has been eliminated.

20. While but one specific embodiment of the invention has been herein shown and described, it will be understood that certain details of the construction shown may be altered or omitted without departing from the spirit of this invention as the same is defined by the following claims.

25. I claim:

30. 1. In a display case having a glazed wall and a refrigerated region insulated from the atmosphere, a pair of vertically spaced shelves in said region visible from the exterior of the case through said glazed wall and adapted to support merchandise for display, an overhead light reflecting surface above the upper shelf, illuminat-

ing means consisting of a source of light and disposed within said refrigerated region at approximately the level of the upper shelf, and a deflector adjacent said illuminating means and interposed between the latter and said glazed wall, 5 a portion of the light rays from said illuminating means being deflected by said deflector from the direction of the glazed wall to the lower shelf, another portion of the light rays being cast directly on the lower shelf, and still another portion of the light rays impinging against the overhead reflecting surface and being reflected from said light reflecting surface to the upper shelf.

10. 2. In a display case having a glazed wall and a refrigerated region insulated from the atmosphere, a pair of vertically spaced shelves in said region visible from the exterior of the case through said glazed wall and adapted to support merchandise for display, a supporting arm mounted on the case intermediate the ends thereof and serving as a support for the upper shelf, a deflector disposed parallelly with and at approximately the level of said upper shelf said deflector having its ends secured to the opposite end walls respectively of the case and being supported intermediate its ends by said supporting arm, said deflector further having an upstanding portion forwardly of the upper shelf and a portion extending rearwardly upwardly from said upstanding portion, illuminating means disposed 15 rearwardly of said upstanding portion of the deflector and below the rearwardly upwardly extending portion of the deflector so that a portion of the light rays from the illuminating means are deflected from the direction of the glazed 20 wall to the lower shelf, and a light reflecting surface extending the length of the case above the upper shelf for reflecting another portion of the light rays from said illuminating means to the upper shelf.

25. 35. 40. GEORGE J. HOPKINS.
